Attorney.

UNITED STATES PATENT OFFICE.

HUGO LEIBE, OF BALTIMORE, MARYLAND.

HARNESS-SADDLE PAD.

SPECIFICATION forming part of Letters Patent No. 331,509, dated December 1, 1885.

Application filed February 6, 1885. Serial No. 155,155. (No model.)

To all whom it may concern:

Be it known that I, HUGO LEIBE, a citizen of the United States, residing at Baltimore, in the State of Maryland, have invented certain new and useful Improvements in Gig-Saddle Pads, of which the following is a specification.

My invention relates to an improvement in gig-saddle pads, and has for its object to produce and stitch by machinery a pad in which a given width of flap will have a pad of broader face than any heretofore so made, and which, when finished, will have the appearance of all hand-made pads.

The accompanying drawings illustrate the invention and show the parts as they appear in the different progressive stages of the manufacture.

Figure 1 is a view of the pad-cover, showing the two reed-covers stitched thereto. Fig. 2 is a cross-section of the same. Fig. 3 is a cross-section of the flap with the pad-cover and reed-covers bowed ready for attachment to the flap. Fig. 4 is a view of the flap and pad-cover attached to it with the reeds. Fig. 5 is another view of the same. Fig. 6 is a view of the pad-spreader. Fig. 7 is a view of the pad material. Fig. 8 is a cross-section of the finished pad on a larger scale. Fig. 9 is a view of a gig-saddle with the improved pad.

The letter A designates the flap or upper back-piece of a gig-saddle; b, the pad-cover, which forms the lower face of the pad and confines the stuffing or pad material c.

The different steps or stages in the manufacture of the pad will now be described in regular order or sequence. Two strips of suitable material to form the reed-covers d are each folded longitudinally by bringing the two edges of the strip together. These folded strips are next placed on the outer surface of the pad-cover, the two edges of each reed-strip being next to and extending with one of the edges of the pad-cover and then secured by a row of stitching, d', as shown in Fig. 1. The reeds e are then inserted in the reed-covers. The pad-cover b is then bowed longitudinally, as shown in Fig. 3, so that the two edges, d', of one reed-cover will confront the two edges of the other reed-cover, and in this position the reed-covers are placed against the inner surface of the flap A, one reed-cover extending along each edge thereof, and each reed-cover

is then secured to the flap by a row of stitches, f, made with a machine and located between the reeds e and the first-named row of stitching. By this means the pad-cover and flap are formed into a tube, as shown by Figs. 4 and 5, for the reception of the stuffing or pad material.

The harness pad "tube" herein described is an article in itself and accomplishes the object of this invention. It is adapted for the reception of the stuffing, which, as stated, may consist of different material, and may be inserted in several ways.

A pad-spreader, g, consists of thin but suitably stiff material—such as pasteboard, wood, or sheet metal—broad enough, when in the tube, to spread the pad-cover over the rows of stitching f along each edge. The spreader g is inserted or slipped endwise in the tube, and the stuffing c has position between the said spreader and pad-cover.

The stuffing or pad material c may be inserted or placed in position in several ways:

First. The felt or other pad material, Fig. 7, may be placed on the inner surface of the pad-cover after the reed-covers have been stitched thereto, and attached to said pad-cover by paste; or the pad material and its cover may be attached by the formation of tufts by a thread in the usual way. When done in this way, the pad-cover is bowed, as shown in Fig. 3, and the pad material, as well as the reed-covers is placed against the inner surface of the flap, and then the rows f of stitches are made and the spreader inserted.

Second. The felt or other pad material may be pasted upon the pad-spreader g, which then, with the pad material on it, is slipped or inserted endwise in the tube.

Third. Curled hair instead of felt may be used as the pad material and stuffed in the tube after the insertion of the spreader.

By stitching the pad-cover b to the flap A and then inserting in the tube thus formed the spreader g, the face b of the pad, (see Figs. 8 and 9,) which is to rest upon the animal's back, is made broader than has heretofore been the case with machine-made pads, and the rows f of stitching which secure the pad-cover to the flap are on the pad side hidden from view.

Heretofore harness-saddle pads have been made by forming the pad-cover and stuffing it

complete with reed-covers attached, and then lastly attaching the stuffed pad to the flap or upper back-piece by "lacing," which is a hand operation. In some of the pads thus made a two-sided cover is employed and sewed together with the reed-covers between and so as to be inclosed by the two sides, and then the outside part of the cover was slit from end to end and turned to bring the reed-covers outward, and finally the edges of the outside part which was slit were sewed together, thus forming a tube for the stuffing material. When stuffed, the said tube was laced to the flap or upper back-piece. In other cases the pad-cover with the stuffing material in it has had the reed-covers attached thereto by stitches running entirely through the stuffing, and then, as already stated, the completed pad was attached to the flap or upper back-piece by hand-lacing. My invention differs from all these in that I can produce an empty tube, of which the flap or upper back-piece is a part, which may be stuffed in various ways. By first sewing the reed-covers *d* to the pad-face cover *b*,

and without the stitches running through the 25 stuffing, as heretofore, and then by a separate row of stitches, *f*, securing each reed-cover to the flap *A* a complete pad is made by sewing-machines, which has the appearance in large part of all-hand-made pads. 30

Having described my invention, I claim and desire to secure by Letters Patent of the United States—

The improvement in the manufacture of harness-saddle pads, consisting of the herein-described pad-tube as an article having each of the two reed-covers *d* secured to the lower face-cover, *b*, by a row of stitching, *d'*, and to the flap or upper back-piece, *A*, by a row of stitching, *f*, located between the reeds and the 35 40 first-named row of stitching, as set forth.

In testimony whereof I affix my signature in presence of two witnesses.

HUGO LEIBE.
